Patented May 7, 1968

210,964

CHESS QUEEN

William A. Gabel, Rte. 2, Wabash, Ind. 46992

Filed Aug. 23, 1967, Ser. No. 8,365

Term of patent 14 years

(Cl. D34—5)

FIG. 1

FIG. 2

FIG. 3

FIG. 1 is a front view of a chess queen showing my new design.

FIG. 2 is a side view of the queen of FIG. 1.

FIG. 3 is a top view of the queen of FIG. 1.

I claim:

The ornamental design for a chess queen, as shown.
